R. P. BENTON.

FEEDING MORTISING MACHINES.

No. 12,287.

PATENTED JAN. 23, 1855.

TAKEN FROM PATENT OFFICE REPORT
1855 - VOL. II -
ONLY DRAWING ACCESSIBLE (1913)

UNITED STATES PATENT OFFICE.

R. P. BENTON, OF ROCHESTER, NEW YORK.

IMPROVEMENT IN FEEDING MORTISING-MACHINES.

Specification forming part of Letters Patent No. 12,287, dated January 23, 1855.

To all whom it may concern:

Be it known that I, R. P. BENTON, of Rochester, in the county of Monroe and State of New York, have invented a new and Improved Mortising-Machine; and I do hereby declare that the following is a full, clear, and exact description of the same, reference being had to the annexed drawings, making a part of this specification, in which—

Figure 1 is a plan or top view of my improved machine. Fig. 2 is a side elevation of the same. Fig. 3 is a detached plan or top view of the ways and screw by which the "stuff" is fed to the cutter. Fig. 4 is a side view of a piece of stuff with mortises shown in it.

Similar letters of reference indicate corresponding parts in the several figures.

The nature of my invention consists in the peculiar means employed for feeding the stuff to the cutter, whereby mortises may be cut in said stuff the required length and depth, the feeding device receiving motion from the same driving-shaft as the cutter and requiring no particular care or attention during its operation.

To enable others skilled in the art to make and use my invention, I will proceed to describe its construction and operation.

A represents the frame of the machine, which may be constructed in any proper manner to support the working parts.

B represents a driving-shaft running in suitable bearings at the lower part of the frame A; and C represents a small shaft on the upper part of said frame, having two pulleys, D E, upon it, the pulley D having a cross-belt, a, passing around it, which belt also passes around a pulley, F, at one end of the driving-shaft B.

G represents a mandrel or arbor at one end of the frame A and at its upper part, said mandrel or arbor being fitted within a suitable head, H, and having a cutter, b, at one end. The mandrel or arbor has a pulley, I, upon it, around which a belt, c, passes, said belt also passing around the pulley E on the shaft C.

J represents a pulley on the driving-shaft B, said pulley J having a belt, d, passing around it, which belt also passes around a pulley, K, on a small shaft, L, the pulley K being fitted loosely on said shaft. At one end of the shaft L there is hung a bevel-wheel, M, in the inner

side of which the pulley K is clutched by operating a lever, N, when it is desired to give motion to the pulley K. The lever N is provided with a spring, r, as shown in Fig. 2. The bevel-wheel M gears into a bevel-wheel, O, which is hung on a vertical shaft, P, having at its upper end a crank, Q, which is attached to the shaft P by a set-screw, e, and thereby rendered adjustable. (See Fig. 1.)

R represents a slide, which works upon two ways, f f, on the upper part of the frame A. (See Fig. 1.) This slide is formed of two parallel strips, g g, connected at their outer ends by cross-strips h h, having grooves in their outer surfaces or edges, in which the inner edges of the ways f f fit.

S is a screw directly underneath the slide R, the ends of said screw working in suitable bearings, i i, on the upper part of the frame A.

T is a pulley on the screw, which pulley has a belt, j, passing around it, said belt also passing around a pulley, U, on the driving-shaft B.

In one of the strips g of the slide R there is a plate, k, secured at one end by a pivot, l. (See dotted lines, Fig. 3.) The outer end of this plate is notched and fits over the edge of a metal bar, V, which is attached to the side of the frame A by parallel bars or arms i i, which are attached to the frame A by pivots m. One end of this metal bar V has a rod, n, secured to it, the end of which is secured to the lever N.

W is a bent lever having its fulcrum at o. The lower arm of this lever bears against the lever N, and keeps the pulley K connected to the bevel-wheel M.

X is a slide, which fits or works between the two strips g g. This slide is provided with a set-screw, p, by which the stuff to be mortised (represented by q) is secured to the slide X, said slide being connected to the crank Q by a rod, s, as clearly shown in Fig. 1.

Y is a spring attached to one of the strips g and to the frame A.

Operation: Motion being communicated to the driving-shaft B, the mandrel or arbor G and cutter b are made to rotate, said mandrel or arbor receiving its motion from the driving-shaft by means of the belts a c. The stuff q is firmly secured in the slide X by means of the set-screw p, and the slide R, which is formed of the strips g g h h, is moved toward the cutter b by the rotating of the screw S, which re-

ceives its motion from the driving-shaft by means of the belt *j*, the plate *k* in one of the strips fitting between the threads of the screw. As the stuff is thus fed to the cutter, it receives a reciprocating motion by means of the crank *Q*, and the stuff is consequently moved back and forth in a direction lengthwise of the mortise, and the length of the stroke or vibration is so regulated by adjusting the crank *Q* by means of the set-screw *e* as to cut the mortises the required length. When the stuff has been fed toward the cutter the required distance, the inner strip, *g*, of the slide *R* strikes against the upper arm of the bent lever *W* and frees the lower arm of the bent lever from the lever *N*, which, in consequence of the spring *r*, throws back the rod and metal bar *V* and raises the plate *k* from the screw *S*, and thereby allows the spring *Y* to draw back the slide *R* to its original position. To cut a succeeding mortise, the stuff is properly adjusted on the slide *X* and the lever *N* operated by hand, so as to throw the pulley *K* in gear with the

bevel-wheel *M*, and motion is again given the driving-shaft.

The above machine works well in practice, and may be attended by a boy only. It is simple, not liable to get out of repair, and not expensive to manufacture. It is well adapted for mortising chair-stuff, &c.

What I claim as new, and desire to secure by Letters Patent, is—

Feeding the stuff to be mortised to the cutter *b* in the manner substantially as herein shown—viz., by means of a rotating screw-rod, *S*, operating upon a slide, *R*, and an adjustable crank, *Q*, which gives a reciprocating motion to the slide *X*, the above parts operating conjointly as herein shown, and for the purpose as set forth.

City of Rochester, October 18, 1854.

R. P. BENTON.
